(57) **CLAIM**

The ornamental design for a non-contact type data carrier, as shown and described.

DESCRIPTION

FIG. 1 is a perspective view of a first embodiment of a non-contact type data carrier showing our new design; and FIG. 2 is a front elevational view thereof.

FIG. 3 is a perspective view of a second embodiment of a non-contact type data carrier showing our new design; and FIG. 4 is a front elevational view thereof.

FIG. 5 is a perspective view of a third embodiment of a non-contact type data carrier showing our new design; and FIG. 6 is a front elevational view thereof.

FIG. 7 is a perspective view of a fourth embodiment of a non-contact type data carrier showing our new design; and FIG. 8 is a front elevational view thereof.

FIG. 9 is a perspective view of a fifth embodiment of a non-contact type data carrier showing our new design; and FIG. 10 is a front elevational view thereof.

FIG. 11 is a front, top, right perspective view of a sixth embodiment of a non-contact type data carrier showing our new design; and,

FIG. 12 is a front elevational view thereof.

The broken lines illustrate the unclaimed portions of the non-contact type data carrier and form no part of claimed design.

1 Claim, 12 Drawing Sheets
